UNITED STATES PATENT OFFICE.

ERNEST F. MECHLIN, OF WASHINGTON, DISTRICT OF COLUMBIA.

DRAFT-RIGGING.

1,356,081.

Specification of Letters Patent. Patented Oct. 19, 1920.

Application filed December 9, 1915, Serial No. 65,886. Renewed March 27, 1920. Serial No. 369,444.

To all whom it may concern:

Be it known that I, ERNEST F. MECHLIN, a citizen of the United States, residing at Washington, in the District of Columbia, 5 have invented certain new and useful Improvements in Draft-Rigging; and I do hereby declare the following to be a full, clear, and exact description of the invention, such as will enable others skilled in the 10 art to which it appertains to make and use the same.

The invention relates to draft rigging for railway cars and more particularly to that 15 class of draft rigging in which a plurality of springs, generally two, are arranged end to end and commonly called tandem draft rigging.

To this end, main features of my invention, generally stated, consist in providing 20 in a tandem spring draft rigging a friction mechanism adapted to be brought into action by movement of the coupler, the said friction mechanism acting to supplement the usual spring mechanism and add to the 25 capacity of the draft rigging.

There are other features of my invention as will appear from a more detailed description of the same taken in connection with the accompanying drawings chosen for the 30 purpose of illustrating one embodiment of the invention, the scope whereof is pointed out in the claims.

Throughout the specification and drawings, like numerals refer to like parts.

35 Fig. 1 is a horizontal central section of a draft rigging, embodying the invention, a portion of the friction casing being shown in plan.

Fig. 2 is a vertical central section of the 40 device shown in Fig. 1.

Figs. 3 and 4 are vertical sections taken respectively on lines 3—3 and 4—4 of Fig. 1, looking in the direction of the arrows.

45 Fig. 5 is a detail elevation of the central portion of the gear, the springs and one of the cheek plates, however, being removed, and

50 Figs. 6, 7 and 8 are detail views, illustrating, respectively, the friction casing, the wedge block and a friction block.

The numeral 9 designates the draft sills to which are connected the tandem stop members or cheek-plates 10 each provided with the usual front stop 11, rear stop 12, 55 an intermediate stop 13, and each also preferably provided with the limiting stops 14.

The numeral 15 designates the front spring member, preferably consisting of the well known arrangement of outer and inner coils, the said spring member being located 60 between the front follower 16 and the front intermediate follower 17. Interposed between the rear intermediate follower 18 and the rear follower 19 is the rear spring member 20 which may likewise comprise inner 65 and outer coil springs.

Connected to the coupler 21 is the yoke, comprising an upper arm 22, a lower arm 23 and a rear connecting member 24. The arms of the yoke are each provided with a thimble block 25, the forward faces of which, in the normal position of the gear, are adapted to contact with the rear face of the front intermediate follower 17, the rear faces of said thimble blocks being preferably spaced slightly from the front face of the other intermediate follower 18.

The numeral 26 designates the friction shell or casing (see Fig. 6) which is preferably rectangular in section and provided 80 with forwardly and rearwardly extending arms 27, the said arms each projecting laterally and being of less vertical height than the casing. The casing is provided with an internal friction surface 28 extending longitudinally thereof. It is also preferably made to fit between the inner faces of the intermediate stops and the thimble blocks 25, and the arms 27 of the casing are adapted to engage the front and rear walls of the 85 intermediate stop and to maintain it in position.

Within the casing are the movable friction elements, preferably comprising a plurality of friction blocks 29 each adapted on 95 their outer faces to slidably engage the friction casing and provided on their inner faces with angularly disposed portions adapted to engage the correspondingly disposed portions 30 and 31 of the wedge block 100 32. Each of the intermediate followers 17 and 18 is preferably H-shape, the upper and lower arms of which are adapted to engage the intermediate stops 13 above and below the arms 27 of the friction casing 26. The 105 follower 17 is provided with a central opening 33 adapted to receive the rear end of a plunger 34 which extends forwardly from the wedge 32 through the spring 15 and into contact with the front follower 16.

110 The operation of the described form of my invention is as follows: When the coupler

is forced rearwardly as in buffing the front follower 16 is moved rearwardly compressing the front spring member 15 against the follower 17 and at the same time the plunger 34 is forced rearwardly causing the friction mechanism to move relatively to the friction closing 26. Owing to the contact of the rear ends of the friction blocks with rear intermediate follower 18, the rear spring member 20 is compressed and thus forces the friction elements 29 with gradually increasing pressure against the friction casing. It will be noted that owing to the clearance space between the thimble blocks 15 and the follower 18 the yoke is entirely relieved from pressure under buffing action and the whole force of the blow is transmitted to the mechanism by means of the followers and plunger member. Under 20 draft strains, owing to the fact that the friction mechanism remains stationary, no frictional resistance is developed and the device operates in the well known manner of the ordinary tandem car spring draft rigging.

It will be seen that because of the arrangement of the various parts of the mechanism the entire force of buffing is transmitted from the coupler to the gear and thence to 30 the sills by rigid cast members entirely independent of the yoke or other draft transmitting member and that the draft strains are entirely tension strains on the yoke or other draft transmitting member thus enabling the use of wrought metal in its most advantageous relation for this element. It will also be noted that in the arrangement of the single embodiment of the device as shown and described that buffing forces, 35 which are of greater magnitude than the draft strains, are resisted by the combined spring and friction action and that draft strains are resisted by the spring action alone.

There are many other advantages of the invention as will be evident from the foregoing description taken in connection with the accompanying drawing among which may be enumerated the elimination of 40 coil shocks, and the form of the friction mechanism which permits of the use of a large number of the parts of the tandem spring draft rigging now commonly in use without change.

Having now fully described the invention, although it is to be noted that the terms used are used in their descriptive and not their limiting sense, what I claim is:

1. In a draft rigging, the combination of 45 a coupler, of a plurality of springs, means for communicating draft forces from said coupler to said springs and means independent of said first named means and involving friction elements movable linearly parallel to the line of draft with a displace-

ment equal to that of the coupler for communicating buffing forces in some only of said springs.

2. In a draft rigging, the combination of a coupler, springs, followers for each of said 70 springs, a casing located intermediate said springs, friction elements coöperating with said casing, and axially arranged means interposed between a follower and said friction elements for causing said friction elements to move coextensively with the said follower to thereby cause a corresponding compression of one of said springs.

3. In a draft rigging, the combination of a coupler, a yoke, of tandem arranged 80 springs, the compression of said springs being equal to the displacement of the coupler, and means involving friction elements for transmitting buffing shocks to the rear spring independently of the yoke.

4. In a draft rigging the combination of a coupler, a plurality of springs arranged in tandem, means for compressing said springs upon a movement of said coupler in either 90 buffing or draft, and friction means arranged between said springs, said friction means being movable by the coupler in one direction only.

5. In a draft rigging the combination of a coupler, a yoke, a plurality of followers, 95 cheek-plates each provided with a plurality of abutments, the said followers normally contacting with said abutments, a casing between the arms of said yoke and adapted to normally contact with two adjacent followers, friction elements within said casing, said elements being movable by a movement of the coupler in one direction only.

6. In a draft rigging, the combination of a coupler, tandem arranged springs, followers for each of said springs, a friction casing located between the said springs, friction means within said casing, and rigid means interposed between a follower and said friction means, said rigid means being adapted 105 to transmit the movement of said coupler in one direction to said friction means and to prevent movement of said means when the coupler is moved in the opposite direction.

7. In a draft rigging, the combination of a coupler, tandem arranged springs, followers for each of said springs, a casing located intermediate said springs, friction elements within said casing, and axially arranged means interposed between a follower and 115 said friction elements for transmitting to said friction elements and one of said springs a movement equal to the displacement of the said follower, and means for preventing movement of said casing.

8. In a draft rigging, the combination of a coupler, a yoke, tandem arranged springs, a casing interposed between said springs, nonrotatable friction elements within said casing and means independent of said yoke 120

and movable by said coupler in one direction only for imparting to said friction elements a movement equal to the displacement of said coupler.

5 9. In a draft rigging, the combination of a yoke, tandem arranged springs within the yoke, a casing interposed between the springs, the yoke being provided with thimble blocks also arranged intermediate the 10 springs, the casing being positioned between the said blocks, and friction means coöperating with said casing.

10 10. In a draft rigging the combination of a yoke, tandem arranged springs within the 15 yoke, follower acting members for the adjacent ends of the springs, thimble blocks connected to the yoke intermediate the ends thereof and adapted to actuate one of said members upon movement of the yoke in one 20 direction, a casing intermediate the said blocks and friction means adapted to co-operate with said casing.

11. In a draft rigging the combination of a pair of cheek-plates each provided with 25 front, rear and intermediate follower stops, a casing adapted to fit between the adjacent faces of the said intermediate stops, said casing having lateral projections adapted to engage the vertical stop faces of said intermediate stops, and friction elements coöperating with said casing.

12. In a draft rigging, the combination of a coupler, a yoke, tandem arranged springs and followers, a casing interposed between said springs, friction elements within said 35 casing and means independent of said yoke, and movable by said coupler for imparting to said friction elements, a movement equal to the movement of the said coupler.

13. In a draft rigging, the combination of a yoke, tandem arranged springs within the yoke, followers for each of the said springs, a casing interposed between the two immediate followers, the yoke being provided with thimble blocks, the said thimble blocks 45 being adapted to engage one of said immediate followers, and being spaced from the other, friction means coöperating with the said casing and means for moving said friction means.

14. In a draft rigging, the combination of a coupler, springs, followers for said springs, means for compressing said springs upon a movement of said coupler, friction means located between said springs, said friction 55 means being movable by the coupler in one direction only, the total movement of said friction means being approximately equal to the displacement of the said coupler.

In testimony whereof I affix my signature. 60

ERNEST F. MECHLIN.
